UNITED STATES PATENT OFFICE.

ADOLF DANGL, OF VIENNA, AUSTRIA-HUNGARY.

METHOD OF COVERING RINGS WITH THREAD.

1,202,033.

Specification of Letters Patent.

Patented Oct. 24, 1916.

Application filed January 21, 1915. Serial No. 3,567.

To all whom it may concern:

Be it known that I, ADOLF DANGL, subject of the Emperor of Austria-Hungary, and resident of 25 Löwengasse, Vienna III, in the Empire of Austria-Hungary, have invented certain new and useful Improvements in Methods for Covering Rings with Threads, of which the following is a description.

10 The present invention relates to a method for covering rings, especially wire rings destined for linen buttons with a single thread in such a manner that the same may not be drawn open and that the ring body is 15 rounded in its cross-section by the thread and may also be covered with thread sections running radially or lying in chords to the circumference of the ring.

In the known methods for covering rings 20 with a thread the thread is passed around the ring so as to form a loop and the thread is drawn through said loop so as to lock it. The loop is thereby formed in the known methods at that side of the ring which is 25 turned away from the path of the shuttle so that the loop must be passed around the ring to come within the reach of the shuttle. This movement is effected by transmitting the loop which has been drawn out by means 30 of a needle provided with a hook to a holding member which is movable into the path of the needle and of the shuttle, said member carrying the loop around the ring body and back to the path of the shuttle whereafter 35 the thread of the shuttle is passed through the loop. Another method consists in catching the loop by means of a second hook of a needle provided with two hooks and drawing it at the outside of the ring after a lateral movement of the latter into the path 40 of the shuttle so as to enable locking.

According to the present invention and in contrast with the two known methods above referred to the loop is formed at that side 45 of the ring which is turned to the path of the shuttle so that the shuttle may directly pass through the loop for locking it. In this method the loop is not turned around the ring but is drawn tight at the same place 50 where it has been formed, while the running thread is laid around the ring when the shuttle passes through the loop. In this manner covering of the ring with thread is very simple in comparison with the known methods 55 above referred to.

If it is desired to produce, by means of

the single thread covering the cross-section of the ring, spun rings, that is to say to cover also the opening of the ring with radial or spoke-like thread sections, the method 60 is carried out in such a manner that the ring body is sewn around one or several times at one point with the thread as stated hereinbefore and that the thread is then passed across the opening of the ring for covering 65 the body thereof at the opposite part in the same manner by sewing it one or several times around the body of the ring, whereafter it is returned to the initial point to be there sewn again around at the side of the 70 first windings, which procedure is repeated until the ring is wholly sewn and spun. Since the needle forming the loop is situated at the same side of the ring as the shuttle so as to be able to draw the loop to said side, 75 it is necessary to draw the thread at the other side of the ring that is to say at the side which is turned away from the path of the shuttle, in order to obtain at this side a thread section bridging the ring opening 80 partly or wholly and extending within the reach of the needle so as to permit formation of the loop, said section being caught by the hook of the needle which passes through the opening of the ring and draws 85 the loop to the side of the shuttle which travels through the loop for locking it. If in the manufacture of spun linen buttons, the ring opening is also to be covered with thread sections the thread is alternatively 90 carried from the one and the opposite side across the opening of the ring and is drawn by the hook of the needle into the path of the shuttle which in its to-and-fro movement forms the thread sections covering the open- 95 ing of the ring which are then locked by the loops running home after the shuttle has been passed therethrough. When forming a button with sections covering the opening of the ring, the ring may also, after having 100 been sewn around at a point one or several times, be turned one or several times around an axis which is situated perpendicularly to the running thread so as to form several thread sections covering the opening, the 105 last of said sections at the side opposite to the hook being used for forming the loop.

In the accompanying drawings Figures 1-12 are representing the several steps of the method as it is carried out by drawing 110 a thread section so as to bridge the opening of the ring and to enable the formation of

the loop. Fig. 13 represents a covered ring provided with radial thread layers covering the opening thereof and being produced by said method. Fig. 14 is a plan view of 5 a spun ring which is manufactured by the same method and is provided with parallel thread layers covering the opening thereof. Figs. 15-17 inclusive are representing a modified form of execution of the method; 10 Figs. 18 and 19 show a spun ring produced by this method in plan view and cross-section, respectively; Figs. 20-33 represent the above referred to method in which the thread section serving to form the loop is 15 obtained by tilting the ring; Fig. 34 is the plan view of a ring produced by this method and Fig. 35 shows a modification.

For carrying the method into practice the ring 1 is covered with a thread by sewing 20 or spinning by means of a hooked needle 2 and a shuttle 3, crossing the path of the needle and traveling across the opening of the ring. While in the known methods the path of the shuttle is situated at the side 25 of the ring which is remote from the needle, the shuttle according to the present invention is traveling at the side of the ring facing the needle so that the running thread 4 is drawn across the ring at the side facing 30 the needle 2 (Fig. 1). If the shuttle has reached one of its two end positions, a guide 5 which is arranged beneath the path of the shuttle and which is oscillating around the ring takes the thread and assisted by the tightener 6 draws the same below the ring 1 so as to form a looped section bridging its opening (Fig. 2). In the following progressive movement of the 35 needle 2 the same passes through the opening of the ring (Fig. 3), catches the upper part of the thread section passing around the guide 5 and bridging the opening of the ring, drawing said section on its return stroke into the path of the shuttle so as to 40 form a loop (Fig. 4). Now the shuttle passes in its movement to the right hand side (Figs. 5 and 6) through the loop, whereupon the thread is slipped off the guide and the hook of the needle so that on the following 45 left hand stroke of the shuttle the loop tightens under the action of a second tightener 6' and is locked to the ring body (Fig. 7). For the purpose of covering the opening of the ring with thread layers 50 which are arranged radially or parallel to a diameter the ring is now turned in its plane or shifted respectively to an extent equal to the distance of two layers or sections and the operation is repeated at the 55 opposite side of the ring. A second guide 5' provided at that side of the ring draws thereby the thread below the opening of the ring (Fig. 8) and the upper section of this part is taken up to form a loop extending 60 within the path of the shuttle (Figs. 9 and 65

10) so that the shuttle in its return movement to the left hand side travels through said loop (Fig. 11) and the loop after having left the guide and the needle is drawn tight under the action of the tightener 6 70 (Fig. 12). The ring is then again turned or displaced and the thread is carried around the left hand side of the ring as already described, until the ring is wholly covered with the thread. Owing to the fact that the 75 thread is tightened and bound to the body of the ring alternatively at opposite sides of the ring during the reciprocating movement of the shuttle, the ring is covered in its step-wise turning movement with radial thread 80 sections 7 as shown in Fig. 13 or with parallel sections 7' as shown in Fig. 14 when it is displaced sidewise instead of being rotated, said layers or sections being fastened to 85 alternating sides of the ring by means of the loops 8. The thread layers covering the opening of the ring are thereby arranged at one face and the loops at the other face thereof (Figs. 13 and 14).

In order to facilitate entering of the 90 shuttle into the loop the same may be tilted by means of the hooked needle by turning the same around its axis to an angle of about 90° as indicated in Figs. 4-6 so that the loop is crossed and opened toward the path of 95 the shuttle so as to avoid misses. Besides, turning of the needle has the effect that the hook takes only the branch of the thread which is to be drawn upward and does not interfere with the other layers or sections 100 of the thread even when the ring is almost completely covered.

As shown in Fig. 15 the loop may however also be distorted in such a manner that the two parts 9 and 9' of the thread are 105 turned from the position shown in Fig. 4 by means of the hooked needle or by any other suitable means through an angle of 180° or somewhat more than 180° into the position indicated in Fig. 15 so that on 110 passing of the shuttle through the loop (Fig. 16) and on subsequently tightening the loop the same is tied into a knot with the running thread 4 (Fig. 17). In this manner the single sections or layers 7, 7' of the 115 thread covering the opening of the ring are held firmly in position (Figs. 18 and 19), and loosening of the windings covering the ring body as it occurs in coverings made according to the known methods, is prevented 120 effectively.

The manufacture of covered rings by sewing and spinning threads around rings of wire or the like may also be effected with the use of knots as mentioned hereinbefore, in 125 the following manner.

If the thread has been fixed at one place of the ring body 1, for example at 7 and the running thread 4 has been stretched above 130 the opening of the ring, the shuttle 3 being

situated at this moment at the left hand side of the ring 1 remote from *b* (Fig. 20), the ring is turned in the direction of the arrow through an angle of 180° in such a manner that the thread 4 passes around the ring as indicated in Fig. 21. Then the shuttle moves into its other end position so that the thread stretched beneath the ring is free to be caught by the hook of the needle 2 (Fig. 22). The needle passing through the opening of the ring takes the thread (Fig. 23) and draws it upward to form the loop (Fig. 24) which after having been twisted (Fig. 25) is traversed by the shuttle 3 returning to the left hand side (Fig. 26) the loop being thereby tightened under the coaction of the tightener 6 which moves in a direction opposite to the direction of movement of the shuttle so that the loop is knotted at a place *a* of the ring body opposite to the preceding knot at *b* (Fig. 27). The shuttle is now again in its initial position as in Fig. 20 but the thread 4 crossing the opening of the ring 1 departs from the place *a* of the ring instead of the place *b* (Fig. 28). Now the ring is turned again through an angle of 180° in the manner described with reference to Fig. 20, as indicated by the arrows in Fig. 28, to the position shown in Fig. 29 and the shuttle moves to its end position at the right hand side (Fig. 30). The needle takes the thread stretched at the lower side of the ring and draws it upward to form the loop which is twisted (Fig. 31) and traversed by the shuttle 3 returning to the left hand side (Fig. 32). The loop after being released from the needle is tightened under the coaction of the tightener 6 (Fig. 33) and is knotted at the place *b* of the ring 1 opposite to the place *a* where the last loop has been knotted. Then the ring is again turned and the operations are repeated as described hereinbefore until the ring is wholly wound and covered with thread. In this manner the ring is provided with a covering formed by a single thread which covering has in distinction from coverings formed by the known methods no loops which are passed around the ring. The ring which is rotated or displaced intermittently or stepwise in its plane and turned about a diameter perpendicular to the path of the shuttle is only spun with radial or parallel threads which are knotted alternatively at opposite sides of the ring. The covering of the ring may, however, also be executed, if desired, by turning the ring through an angle of twice or more times 180° whereafter the thread is knotted. In this manner the ring is provided with one or more unknotted thread sections 10 (Fig. 35) between the knotted sections 7'. Having now described my invention what I claim and desire to secure by Letters Patent is:

65 1. A process for enveloping rings with

threads comprising running a thread around a ring body in the direction of a chord over the ring, bringing it around the ring body to the under portion of the ring and drawing it in a loop through the opening of the ring, then passing the thread supply through the loop and drawing the loop tight, and then repeating these alternately on opposite sides of the ring and intermittently moving said ring in its own plane, until the ring is completely spun over and sewed around.

2. A method for covering rings with thread, which comprises passing a thread section across the opening of the ring, taking said section and drawing it through the ring so as to form a loop, passing the thread supply through said loop on the side of the ring on which said loop is formed, tightening said loop and stepwise moving the ring in its plane before repeating said series of operations, substantially as described.

3. A method for covering rings with thread which comprises passing a thread section across the face of the ring, taking said section and drawing it through the opening of the ring so as to form a loop, twisting the loop more than 90°, moving the thread supply through said loop, tightening the loop and stepwise moving the ring in its plane before repeating said series of operations, substantially as described.

4. A method for covering rings with thread which comprises passing a thread section across the face of the ring, taking said section and drawing it through the opening of the ring so as to form a loop, turning said loop through an angle of more than 180°, moving the thread supply through said loop, tightening and knotting the loop to the ring body, and stepwise moving the ring in its plane before repeating said series of operations, substantially as described.

5. A method for covering rings with thread, which comprises passing a thread section across the face of the ring, catching said section by means of a hooked needle and drawing it through the ring so as to form a loop, moving the thread supply through said loop, tightening the loop, carrying the thread to the opposite side of the ring, repeating these operations to form a winding around its body, and stepwise moving the ring in its plane before each repetition of said operations, substantially as described.

6. A method for covering rings with thread, which comprises covering the ring body with a number of windings, turning the ring about a diameter through an angle of 180° or a multiple thereof, so as to obtain thread sections crossing the opening of the ring at its face remote from the path of the thread supply, taking the last formed of said sections and drawing it through the

opening of the ring so as to form a loop, turning the loop, moving the thread supply through said loop, locking the loop and stepwise moving the ring in its plane before repeating said series of operations, substantially as described.

7. A method for covering rings with thread, which comprises passing a section of the thread over the opening of the ring at the 10 face thereof which is remote from the path of the thread supply, catching said section and drawing it through the opening of the ring so as to form a loop adapted to be traversed by the reciprocating thread supply, traversing the loop by the thread supply, tightening and locking the loop, passing 15

the thread beneath the opening of the ring in an opposite direction, taking and drawing it through the opening of the ring so as to form a loop, traversing said loop by the 20 thread supply on its return movement, tightening and locking the loop on the ring body and stepwise moving the ring in its plane before repeating said series of operations, substantially as described.

25

In testimony whereof I have signed my name to this specification in the presence of two subscribing witnesses.
